(57) **CLAIM**

The ornamental design for a finger cot for handling paper, as shown and described.

DESCRIPTION

FIG. 1 is a perspective view of a finger cot for handling paper; FIG. 2 is a side elevation view of the claimed design while in use;

FIG. 3 is a side elevation view of the claimed design, while in use, with the tip shown in an alternate position;

FIG. 4 is a side view of the claimed design as shown in FIG. 1;

FIG. 5 is a side view of the opposite side thereof;

FIG. 6 is a top view thereof;

FIG. 7 is a bottom view thereof;

FIG. 8 is an end view thereof, looking into the finger-receiving opening; and,

FIG. 9 is an opposite end view thereof.

The human finger shown by dashed lines in the drawings represents environmental matter and forms no part of the claimed design.
